(57) **CLAIM**

The ornamental design for an ultraviolet disinfection apparatus, as shown and described.

DESCRIPTION

FIG. 1 is a side perspective view of an ultraviolet disinfection apparatus showing my new design;

FIG. 2 is a front view thereof;

FIG. 3 is a rear view thereof;

FIG. 4 is a side view thereof;

FIG. 5 is an opposite side view thereof;

FIG. 6 is a top view thereof; and,

FIG. 7 is a bottom view thereof.

The broken line(s) shown in the figures represent portions of the ultraviolet disinfection apparatus that form no part of the claimed design.
